UNITED STATES PATENT OFFICE

ERNEST W. THIELE, OF CHICAGO, ILLINOIS, ASSIGNOR TO STANDARD OIL COMPANY, OF WHITING, INDIANA, A CORPORATION OF INDIANA

APPARATUS FOR CARBONIZATION OF COAL

Original application filed May 14, 1928, Serial No. 277,766. Divided and this application filed July 27, 1929.
Serial No. 381,480.

This invention relates to apparatus for the carbonization of coal, and particularly to low temperature carbonization thereof.

The present application constitutes a division of my application Serial No. 277,766, filed May 14, 1928.

The invention will be readily understood from the following description in conjunction with the accompanying drawing which shows 10 diagrammatically and in elevation with parts in section a suitable apparatus in which the carbonization may be carried out.

Referring to the drawing, 10 represents a heater for coke which may suitably be constituted by a relatively large chamber provided at its top with a valved loading hopper 11 and at its bottom with suitable air supply means 12. From the base of the heater 10 leads an outlet conduit 13 for the heated coke. 20 The heater 10 is provided near its bottom with suitable mechanical means for causing the coke to move into the conduit 13. This mechanical means may suitably be a rotatable bottom 14 which cooperates with stationary members 15 so as to supply highly heated coke to the conduit 13.

A coal heater 16, which may suitably be constituted by an elongated revolving drum of the revolving kiln type, is located in juxtaposition to the coke discharge conduit 13. The discharge end of said drum leads into a conduit 17. In order to facilitate the flow of fresh coal through the preheater drum 16 the interior of the drum 16 may be provided 35 with one or more spiral ribs or veins 16a.

From an upper point of the heater 10 a conduit 18 leads to a combustion chamber 19, which is provided with a conduit 20 for supplying air to effect the combustion of combustible gases therein. From the combustion chamber 19 a conduit 21 leads into the coal-discharge end of the heater 16 so as to supply the hot gaseous products of combustion thereto for the purpose of preheating coal therein. 40 The coal-supply end of the coal heater 16

is provided with a stationary end closure 22, into which connects a conduit 23 for supplying coal to the heater 16 and a conduit 24 for conducting the outgoing products of combustion to a suitable stack (not shown). A 50 by-pass 25 provided with a fan 26 may be provided between conduit 24 and combustion chamber 19 so that a certain amount of the gases can be recirculated through the coal heater 16, as desired.

The hot coke conduit 13 and the hot coal conduit 17 lead into an enlarged conduit 27 which conducts the mixed coal and coke into a coking chamber 28 which is preferably a downwardly flaring conical retort provided 60 at its base with a rotating spiral coke extractor 29 of a known type. From the upper part of the retort 28 an outlet 30 leads to suitable tar condensating and gas purifying apparatus (not shown).

If desired, a suitable distributor 31 may be provided in the upper part of the retort. Such distributor may suitably comprise a cage formed of bars and adapted to be actuated by a pulley 32 located on the outside of 70 the retort.

The method of operation is as follows: Freshly crushed coal is supplied by conduit 23 to the coal heater 16 which is rotated during the operation so as to thoroughly expose 75 the coal to the effect of the hot gases and raise its temperature as high as possible without losing heating value, for example, to a temperature of about 675° F. Similarly crushed coke, which may be part of the coke produced 80 in the process or which may be from any other source is placed in the coke heater 10 and subjected to partial combustion therein, air being admitted by inlet 12, so that it is raised to a high temperature, for example, about 85 2000° F. Coke at this temperature is fed to the hot coke conduit 13 at the rate of about half the coal supply to the hot coal conduit 17. The hot coal and hot coke pass into the retort 28 and are thoroughly mixed one with 90

the other by the distributor 31 which spreads the mixture uniformly therein. In this way the mixture attains a temperature of about 1100° F. which is sufficient for low temperature carbonization in the course of a few moments. When the retort 28 becomes filled to a suitable degree the coke extractor 29 is operated continuously so as to maintain the level of coke in the retort 28 substantially constant.

10 The gas and other volatile matters produced during the coking pass off by conduit 30 and are treated in the usual manner which need not be described here.

The gases resulting from the partial combustion in the heater 10 contain substantial quantities of carbon monoxide and in this respect are similar to producer gases. The gases pass from the heater 10 into the chamber 19 where they undergo combustion with the aid 15 of air introduced by pipe 20. The products of this combustion pass by a conduit 21 into coal heater 16 and preheat the coal in the manner already described. By regulating the fan 26 a certain proportion of the flue gases 20 can be recirculated through the coal heater for the purpose of preventing the coal from 25 attaining a temperature therein which would cause loss of heating value.

It must be understood that the temperature 30 and the relative proportions of coke and coal specified herein are stated by way of example only and the invention is not intended to be limited thereto, since it is obvious that these 35 conditions can be altered within wide limits for the attainment of a mixture of coke and coal in the retort 28, which will insure the coking or carbonization of the coal therein. About 5 or 6% of the coke is consumed in conducting the operation.

40 It will be thus understood that the coking operation can be conducted in a continuous manner, and it is further pointed out that the admixture of coke prevents to a great extent the tendency of the coke which is being produced from adhering to the walls of the retort 28.

Since no exterior heating is employed it is preferred to insulate the whole apparatus to prevent loss of heat.

50 Although the present invention has been described in connection with the details of a specific apparatus and of a specific example, it is not intended that such details shall be regarded as limitations upon the scope of the 55 invention, except in so far as included in the accompanying claims.

I claim:

1. An apparatus for coking coal comprising a retort, means for partially burning coke to heat it to a high temperature, means for conveying said highly heated coke to said retort, a chamber for preheating fresh coal to be coked, means for supplying preheated coal from said preheating chamber to said retort, means for withdrawing volatile mat-

ter from said retort, and means for withdrawing coke from said retort.

2. An apparatus for coking coal comprising a vertical retort, means for subjecting coke to partial combustion to heat it to a temperature sufficient to effect coking of coal, means for supplying said heated coke to said retort, means for supplying finely divided coal to said retort so that said coke and coal become intimately admixed therein, means for withdrawing volatile matter from the top of said retort and means for continuously withdrawing coke from the bottom of said retort.

3. An apparatus for coking coal comprising a vertical retort, means for subjecting coke to partial combustion to heat it to a temperature sufficient to effect coking of coal, means for supplying said heated coke into the top of said retort, means for supplying finely divided coal into the top of said retort, a mixing device in said retort adapted to distribute said coke and coal in intimate admixture, a conduit for withdrawing volatile matter from said retort, and means for continuously withdrawing coke from the bottom of said retort.

4. An apparatus for coking coal which comprises a chamber for heating finely divided coke, means for supplying air to said chamber for the partial combustion of coke therein whereby said coke is highly heated, a vertical retort, means for continuously supplying heated coke from said coking chamber to said retort, means for supplying finely divided coal to said retort in intimate admixture with said highly heated coke, a conduit for withdrawing volatile matter from said retort, and means for continuously withdrawing coke from the bottom of said retort.

5. An apparatus for coking coal comprising a rotating drum for heating coal, means for supplying finely divided coal to said drum, means for causing the coal to pass through said drum in a given direction of flow, means for supplying hot gases to said drum in a direction countercurrent to the direction of movement of the coal whereby the coal is preheated, means for highly heating finely divided coke by partial combustion of the same, a retort, means for supplying the preheated coal and the highly heated coke to said retort in intimate admixture, means for withdrawing volatile matter from said retort, and means for continuously withdrawing coke from said retort.

6. An apparatus for coking coal comprising a chamber for heating finely divided coke, means for supplying air to said coke-heating chamber to effect partial combustion of the coke therein thereby raising the coke to a high temperature, a rotatable drum, means for supplying finely divided coal thereto, means for causing the coal to pass through said drum in a given direction of

flow, a combustion chamber for the gases from the coke heater, a conduit for supplying products of combustion from said combustion chamber to said rotating drum in 5 countercurrent to the coal therein to preheat the same, a vertical retort, means for continuously supplying the highly heated coke from said coke heater into the upper end said retort, means for supplying preheated 10 coal from said rotatable drum to the upper end of said retort, means for intimately mixing said highly heated coke and coal in said retort, a conduit for withdrawing volatile matter from said retort, and means for continuously withdrawing coke from the bottom 15 of said retort.

7. An apparatus for coking coal comprising a chamber for heating finely divided coke, means for supplying air to said coke heating 20 chamber to effect partial combustion of the coke thereby raising it to a high temperature, a rotatable drum, means for supplying finely divided coal to said retort, means for causing the coal in said drum to pass there- 25 through in a given direction of flow, a combustion chamber for the gases from said coke heater, a conduit for supplying products of combustion from said combustion chamber to said rotatable drum in countercurrent to 30 the movement of the coal therein, means for causing gases from said coal heater to recirculate therethrough, a vertical retort, means for continuously supplying highly heated coke from the coke heater into the upper end 35 of said retort, means for supplying preheated coal from the rotatable drum to the upper end of said retort, means for intimately mixing said coke and coal in said retort, a conduit for withdrawing volatile matter from 40 said retort, and means for continuously withdrawing coke from the bottom of said retort.

8. An apparatus for coking coal comprising an externally unheated vertical retort, means for subjecting coke to combustion to 45 heat it to a temperature sufficient to effect heating of coal, means for supplying highly heated coke to said retort, means for supplying coal to said retort so that said coke and said coal become admixed therein whereby 50 heat is imparted to said coal from said heated coke, means for withdrawing volatile products from the upper portion of said retort, and means for withdrawing coke from the lower portion of said retort.

55 9. An apparatus for coking coal comprising an externally unheated vertical retort, means for subjecting coke to a combustion to heat it to a temperature sufficient to effect coking of coal, means for supplying said heated finely divided coke into the upper portion of said retort, means for supplying finely divided coal into the upper portion of said retort, means within said retort for admixing said hot coke and said coal whereby heat 60 of the coke is imparted to said coal, a conduit

for withdrawing volatile products from said retort, and means for withdrawing coke from the lower portion of said retort.

10. An apparatus for coking coal which comprises a chamber for heating finely di- 70 vided coke by partial combustion of said coke to a temperature sufficient to effect coking of coal, an externally unheated vertical retort, means for supplying the said heated coke to the interior of said unheated retort, means for supplying finely divided coal to 75 said retort whereby said coal comes into contact with said heated coke, a conduit for withdrawing volatile products from said re- 80 tort, and means for withdrawing coke from the lower portion of said retort.

11. An apparatus for coking coal comprising means for preheating coal, means for sup- 85 plying finely divided coal to said preheating means, means for highly heating finely di- vided coke by partial combustion of the same, an externally unheated vertical retort, means for supplying the highly heated coke from 90 said coke-heating means to said retort, means for supplying the preheated coal from said preheating means to said retort whereby 95 said preheated coal comes into contact with said coke and thereby receives additional heat, means for withdrawing volatile products from said retort, and means for with- drawing coke from said retort.

12. An apparatus for coking coal comprising means for preheating coal comprising a rotatable drum adapted to have hot gases 100 passed therethrough, means for supplying finely divided coal to said drum, means for highly heating finely divided coke by partial combustion of the same, an externally un- 105 heated vertical retort, means for supplying the highly heated coke from said coke-heating means to said retort, means for supplying the preheated coal from said preheating means to said retort whereby said preheated coal comes into contact with said coke and thereby receives additional heat, means for 110 withdrawing volatile products from said retort, and means for withdrawing coke from said retort.

13. An apparatus for coking coal comprising means for preheating coal, means for supplying finely divided coal to said preheat- 115 ing means, a chamber for heating finely di- vided coke by partial combustion of said coke, an externally unheated vertical retort, means for supplying the highly heated coke from 120 said coke-heating means to said retort, means for supplying the preheated coal from said preheating means to said retort whereby said preheated coal comes into contact with said coke and thereby receives additional heat, means for 125 withdrawing volatile products from said retort, and means for withdrawing coke from said retort.

14. An apparatus for coking coal comprising an externally unheated retort, means for 130

subjecting coke to combustion to heat it to a high temperature, means for supplying said highly heated coke to said retort, a coal pre-heating chamber, means for supplying coal 5 to said preheating chamber, means for passing hot gases in heat exchange relation with the coal in said preheating chamber, means for passing the preheated coal from said chamber to said retort, means for withdrawing volatile products from said retort, and means for withdrawing coke from said retort.

ERNEST W. THIELE.
